UNITED STATES PATENT OFFICE

105,331

DESIGN FOR A GOLF BAG OR SIMILAR ARTICLE

John K. Hotze, St. Louis, Mo.

Application July 8, 1935, Serial No. 57,559

Term of patent 7 years

To all whom it may concern:

Be it known that I, John K. Hotze, a citizen of the United States, residing at St. Louis, and in the State of Missouri, have invented a new, original, and ornamental Design for a Golf Bag or Similar Article, of which the following is a specification, reference being had to the accompanying drawing, forming part thereof.

Figure 1 is a plan view of the golf bag, a portion of the handle being broken away for convenience in illustrating my new design.

The dominant feature of the design resides in the portion shown in solid lines having the characteristics of an oblong shape when viewed from the top, as shown in Fig. 1, and upper and lower straight or horizontal portions, joined by reverse or ogee portions when viewed from the side, as shown in Fig. 2.

I claim:

The ornamental design for a golf bag or similar article, as shown and described.

JOHN K. HOTZE.
